[57] CLAIM

The ornamental design for a set of fender trim rails, as
shown and described.

DESCRIPTION

FIG. 1 is a perspective view of a set of fender trim rails
showing my new design; the broken lines are shown for
illustrative purposes only and form no part of the claimed
design;

FIG. 2 is a top view of one of the trim rails shown in FIG.
1;

FIG. 3 is a side view of one of the trim rails shown in FIG.
1, the opposite side being a mirror image of that shown; and,

FIG. 4 is a front view of one of the trim rails shown in FIG.
1, the rear view being a mirror image of that shown.

The bottom view of the design is not visible in its normal or
intended use because it is substantially obscured by a
motorcycle fender.
